DESIGN FOR A CANOPY FOR BABY CARRIAGE

Matilda D. Welsh, Ladue Village, Mo.

Application June 22, 1940, Serial No. 93,185

Term of patent 14 years

To all whom it may concern:

Be it known that I, Matilda D. Welsh, a citizen of the United States, residing at Ladue Village, county of St. Louis, State of Missouri, have invented a new, original, and ornamental Design for a Canopy for Baby Carriage, of which the following is a specification, reference being had to the accompanying drawing, forming part thereof.

Fig. 1 is a perspective view of a canopy for baby carriage showing my new design, taken substantially from one side of the canopy the other side being the same; and

Fig. 2 is a rear elevational view thereof.

I claim:

The ornamental design for a canopy for baby carriage, as shown and described.

MATILDA D. WELSH.
